(57) **ABSTRACT**

A new and distinct avocado of *Persea americana* P. Mill.
named 'BEN-YA'ACOV1', particularly characterized by
lower tendency towards alternate bearing, *Phytophthora
cinnamomi* and salinity resistance, and induced productivity
on the grafted varieties.

4 Drawing Sheets

1

Botanical name of the genus and species of the plant
claimed: *Persea americana* P. Mill.

Varietal denomination: 'BEN-YA'ACOV1'.

BACKGROUND OF THE INVENTION

The present invention relates to a new and distinct variety
of avocado tree, botanically known as *Persea americana* P.
Mill. of the Lauraceae family, and hereinafter referred to by
the variety denomination 'BEN-YA'ACOV1'.

Clonal avocado rootstocks were developed in Israel on a
small scale between the years 1962 to 1977 and on a large
scale in the years following. During the entire period about
220 different rootstocks have been developed in an attempt
to solve soil problems caused by stress factors such as
salinity, lime, poor aeration and root-rot, and various com-
binations of these factors, while simultaneously improving
productivity. Uniformity among trees and dwarfness were
also taken into account as part of the search for better
rootstocks. The development process included field eval-
uation on a very large scale, in which 350 experiments and
65000 trees took part.

The new *Persea americana* P. Mill. 'BEN-YA'ACOV1'
was discovered and selected by the inventors, Avraham Ben
Ya'akov, Miriam Silberstein, and Vered Irihimovitch, grow-
ing in a cultivated area in the late 1970's in Ma'agan
Michael, Israel. The new *Persea americana* P. Mill. 'BEN-
YA'ACOV1' was selected by the inventors based on lower
tendency towards alternate bearing, *Phytophthora cinna-
momi* and salinity resistance, induced productivity on the
grafted varieties.

2

Asexual propagation of the new *Persea americana* P.
Mill. variety by the Frolich method for vegetative propa-
gation was first performed in March 1980 in the Volcani
5 Center, Israel and has demonstrated that the combination of
characteristics as herein disclosed for the new variety are
firmly fixed and retained through successive generations of
asexual propagation. The new variety propagates true-to-
type.

BRIEF DESCRIPTION OF THE INVENTION

15 The following traits have been repeatedly observed and
are determined to be characteristics of 'BEN-YA'ACOV'
which in combination distinguish this avocado tree as a new,
unique and distinct variety:

1. lower tendency towards alternate bearing;
2. *Phytophthora cinnamomi* resistance;
3. Salinity resistance; and
4. Induced productivity on the grafted varieties.

25 Of the many varieties known to the present inventors, the
most similar in comparison to the new *Persea americana* P.
Mill. 'BEN-YA'ACOV1' is *Persea americana* P. Mill.
'DEGANIA 117' (unpatented) which differ from the new
30 variety 'BEN-YA'ACOV1' in the characteristics described
in Table 1:

TABLE 1

Comparison with most similar variety.		
Characteristic	New Variety 'BEN-YA'ACOV1'	Comparison Variety 'Degania 117'
Productivity	High productivity as rootstock for 'Pinkerton'	High productivity as rootstock for 'Hass', 'Etinger' and 'Pinkerton'
Tree vigor characteristic	Dwarfing type	Vigorous type

BRIEF DESCRIPTION OF THE PHOTOGRAPHS

The accompanying photographs illustrate the overall appearance of the new *Persea americana* P. Mill. variety 'BEN-YA'ACOV1' showing the colors as true as is reasonably possible with colored reproductions of this type. Colors in the photographs may differ slightly from the color values cited in the detailed morphological description, which accurately describe the color of 'BEN-YA'ACOV1'. Plants shown in the photographs are approximately two years old.

FIG. 1—Shows a typical tree of 'BEN-YA'ACOV1'.

FIG. 2—Shows a typical leaf upper surface (left) and under surface (right) of 'BEN-YA'ACOV1'.

FIG. 3—Shows a typical shoot of 'BEN-YA'ACOV1'.

FIG. 4—Shows a typical vegetative bud of 'BEN-YA'ACOV1'.

DETAILED BOTANICAL DESCRIPTION

The new *Persea americana* P. Mill. 'BEN-YA'ACOV1' has not been observed under all possible environmental conditions. The phenotype of the new variety may vary with variations in environment such as temperature, light intensity, day length, soil or pruning without any change in the genotype of the avocado plant.

The aforementioned photographs, together with the following observations, measurements and values describe trees of 'BEN-YA'ACOV1' as grown in The Volcani Center, Israel, under conditions which closely approximate those generally used in commercial practice. The described plants were propagated by the Frolich method and planted at a distance of 6×4 m in sandy red loam soil at an elevation of about 30 meters above sea level with 700-1000 m³ per dunam per season of irrigation and N:P:K 30:30:5 of fertilizers. Average annual rainfall is about 550 mm, with an average 350 mm of rainfall in winter (December to February). Mean diurnal minimum temperature in January is 7.2° C., and mean diurnal maximum temperature in July is 30.8° C.

Unless otherwise stated, the detailed morphological description includes observations, measurements and values taken from 2014 to 2015 and based on two-year-old 'BEN-YA'ACOV1' plants/trees grown in the orchard in The Volcani Center, Israel. Quantified measurements are expressed as an average or a range of measurements taken from a number of plants of 'BEN-YA'ACOV1'. The measurements of any individual plant, or any group of plants, of the new variety may vary from the stated average or range.

Color references are made to The Royal Horticultural Society Colour Chart (R.H.S.), (1986 edition), except where general colors of ordinary significance are used. Color values were taken under daylight conditions in full sunlight in the Volcani Center, Israel.

All of the plants of 'BEN-YA'ACOV1', insofar as they have been observed, have been consistent in all the characteristics described below.

Classification:

Botanical.—*Persea americana* P. Mill.

Propagation: Frolich method.

Growing conditions:

Light intensities.—Full sunlight.

20	January	February	March	April	May	June
Mean maximum air temperature (° C.)	17.8	18.1	20.1	24.5	27	29.2
Mean minimum air temperature (° C.)	7.2	7.1	8.8	11.5	14.6	17.9
Mean rainfall (mm)	140.5	96.9	66.1	17.5	2.2	—
30	July	August	Sep-tember	October	November	De-cember
Mean maximum air temperature (° C.)	30.8	31.2	30.4	28.3	24.1	19.7
Mean minimum air temperature (° C.)	20.6	21.2	19.4	16	11.8	8.6
Mean rainfall (mm)	—	—	0.4	20.4	76.2	130.3

Fertilization.—A balanced fertilizer with level of N:P:K 30:30:5.

Growth regulators.—As used in commercial practice.

TABLE OF CHARACTERISTICS

TREE:	
Age:	Observed trees were two years old.
Tree	Type: West Indian. Vigor: strong. Growth habit: semi-upright. General shape: globular. Density of canopy: dense. Height: about 2 m. Number of main branches: 2. Attitude: semi-upright. Diameter at 50 cm height: about 25 cm. Surface Texture: very rough. Color of Bark: RHS 199B.
Main branch	Lenticels: Not visible.
Trunk	Color: light green RHS 144 B. Color of lenticel: medium green RHS 144 A. Shape of lenticels: elongated or rounded. Density of lenticels: dense. Size of lenticel: about 1 mm.
Young shoot	

-continued

TABLE OF CHARACTERISTICS	
TREE:	
Age:	Observed trees were two years old.
Shoot	Length of internode: 35-56 cm. Thickness: 10-13 mm. Color: light green RHS 144 B.
Vegetative bud	Shape: conical. Length: 3-5 mm. Color: medium to dark green RHS 152 A. Pubescence: strong.
Young leaf	Color of pubescence of petiole: yellow-white RHS 158D. Color of upper side: medium to dark green RHS 137 A. Color of lower side: medium green RHS 138 B.
Leaf	Attitude relative to shoot: horizontal.
Leaf blade	Length: 22-24 cm. Width: 70-97 mm. Ratio length/width: longer than broad. Shape: elliptic. Shape of apex: obtuse. Tip: acuminate. Color of upper side: medium to dark green RHS 137 A. Color of lower side: medium grayish green RHS 147 C. Anthocyanin coloration: absent. Shape in cross section: v shaped. Shape of base: obtuse. Twisting along whole length: absent. Twisting of apex: present. Undulation of margin: strong. Relief of venation on upper surface: at level. Relief of venation on lower surface: raised. Color of veins of upper side: medium yellow green RHS 151 A. Color of veins of lower side: medium yellow green RHS 151 A. Number of secondary veins: about 7. Distance of secondary veins: 2-3 cm. Density of pubescence on upper surface: sparse. Density of pubescence on lower surface: medium. Color of hairs: green-yellow RHS 1D. Anise aroma: present.
Petiole	Length: 25-35 mm. Thickness: 3-4 mm. Color: medium yellow green RHS 151 A. Pubescence: weak. Cross section: rounded and truncate. Lenticels: few to medium.
